(57) **CLAIM**

The ornamental design for a welding component as shown and described.

DESCRIPTION

FIG. 1 is a front perspective view of an embodiment of a welding component;

FIG. 2 is a rear perspective view of the welding component of FIG. 1;

FIG. 3 is a front view of the welding component of FIG. 1; FIG. 4 is a rear view of the welding component of FIG. 1; FIG. 5 is a first side view of the welding component of FIG. 1;

FIG. 6 is a second side view of the welding component of FIG. 1;

FIG. 7 is a top view of the welding component of FIG. 1; and,

FIG. 8 is a bottom view of the welding component of FIG. 1.

In the drawings, the broken lines depict portions of the welding component that form no part of the claimed design.

1 Claim, 5 Drawing Sheets
